CLAIM

The ornamental design for a housing for hairdresser's mirror and storage shelves, substantially as shown and described.

DESCRIPTION

FIG. 1 is a front perspective view of a housing for hairdresser's mirror and storage shelves showing our new design;

FIG. 2 is a top plan view thereof.

FIG. 3 is a bottom plan view thereof.

FIG. 4 is a front elevational view thereof.

FIG. 5 is a left side elevational view thereof.

FIG. 6 is a rear elevational view thereof; and

FIG. 7 is a right side elevational view thereof.
